UNITED STATES PATENT OFFICE.

ELISHA H. OSBORN, OF DES MOINES, IOWA.

MAGNETIC SEPARATOR FOR THRESHING-MACHINES.

SPECIFICATION forming part of Letters Patent No. 570,496, dated November 3, 1896.

Application filed January 24, 1896. Serial No. 576,747. (No model.)

To all whom it may concern:

Be it known that I, ELISHA H. OSBORN, a citizen of the United States of America, and a resident of Des Moines, in the county of Polk and State of Iowa, have invented a new and useful Improvement in Magnetic Separators for Threshing-Machines, of which the following is a specification.

Heretofore much trouble has been experienced by threshermen owing to the frequency with which the teeth of the cylinder or concave of the machine are broken by reason of the choking of the cylinder by excessive feeding or the presence of pieces of metal or rock or wood in the bundles of grain. When one tooth is broken from either the cylinder or concave, it naturally passes through the machine, is conveyed by the elevator to the tail spout or shoe, from which the tailings are delivered to the cylinder for rethreshing, and falls into and passes through the machine again and again, causing material and expensive damage by destroying additional teeth. This trouble is experienced to the greatest degree in machines which employ automatic or self-feeding apparatus, since under such circumstances no attendant is adjacent to the shoe to remove the teeth as they appear and prevent them from reentering the machine.

It is the object of this invention to provide means for automatically removing broken teeth or other metallic objects from the tailings as said tailings reenter the machine and prevent said teeth from continuing their damaging course.

My invention consists in locating a magnet in the path of travel of the tailings, which magnet is of such character as to attract and retain the broken teeth, and also in the provision of an alarm indicating the presence of a tooth on the magnets.

My invention consists, further, in locating in the path of travel of the tailings from the machine to the cylinder a series of metallic bars arranged in close juxtaposition to each other and connected with an alarm indicating the presence of a tooth or other foreign metallic body in contact with the said bars.

My invention consists, further, in the construction, arrangement, and combination of parts hereinafter set forth, pointed out in my

claims, and illustrated by the accompanying drawings, in which—

Figure 1 is a side elevation of a portion of a threshing-machine, showing my invention applied thereto. Fig. 2 is a sectional elevation longitudinally of the delivery spout or shoe, showing my invention applied thereto. Fig. 3 is a plan of the delivery spout or shoe to which my invention is applied. Fig. 4 is a plan of a delivery spout or shoe to which a modified form of my invention is applied.

In the construction of the machine as shown the numeral 10 designates a delivery spout or shoe which is suspended in a common manner above and adjacent to the entrance to the breast of a threshing-machine, and a delivering-elevator 11 of common form discharges the tailings of the machine into the outer end portion of the said shoe. The shoe 70 may be of any ordinary construction, preferably with an open top, and may be provided with any ordinary means of screening the tailings and discharging said tailings.

The side boards of the shoe 10 are apertured in series in inclined planes, and a series of bars or "magnets," as they hereinafter will be termed, 12 are mounted in the said apertures at slight distances of separation from each other and provide a slotted way or screen 80 to receive the tailings from the elevator 11. The magnets 12 are of the character designated as "permanent" magnets and are of such size and strength of magnetism as will attract and retain broken teeth or other small metallic objects when brought in close relation therewith. The magnet nearest the outer end of the shoe is connected to a circuit-wire 13, which circuit-wire leads therefrom through a bell 14, mounted on the elevator 11, and 90 through a battery 15, also mounted on said elevator. The circuit-wire leads from the battery 15 to the magnet adjacent to the one nearest the end of the shoe, and the remaining magnets are in like manner alternately connected to the circuit-wires. By this construction an electric circuit is not complete until two adjacent magnets are electrically connected, as, for instance, by a tooth lying upon and engaging both of said magnets.

In the form of device shown in Fig. 4 the magnets are of horseshoe shape and overlap

each other in pairs, one magnet of each pair being connected to the opposite end portions of the circuit-wire 13. The horseshoe-magnets are positioned in different horizontal planes in order that they may overlap without such contact as will establish a circuit under normal conditions.

In the practical use of this device when a tooth is deposited in the shoe from the elevator it immediately is attracted to and contacts with one or two or more of the magnets and is retained by said magnets and prevented from re-entering the machine. When a tooth engages two or more of the magnets simultaneously, a circuit is established through the battery and bells and the bells are rung, thus sounding an alarm and indicating the presence of a tooth in the shoe. Upon hearing the alarm an attendant may remove the tooth from the magnets and thereby avoid the possibility of its accidental release or the running down of the battery.

I claim as my invention—

1. In a threshing-machine, a series of metallic bars located in the path of travel of the tailings from the machine to the cylinder and forming a bottom over which the tailings must pass to the cylinder, and an electric bell-circuit connected with said metallic bars, which bell-circuit is normally open and is closed by the contact with said bars of a foreign metallic body.

2. In a threshing-machine, a magnet located in the path of travel of the tailings from the machine to the cylinder and a bell-circuit 35 electrically connected with said magnet and operated by the contact of a metallic body with said magnet.

3. In a threshing-machine, a shoe through which the tailings pass from the machine to the cylinder, a series of metallic bars arranged in juxtaposition to each other within said shoe and forming a bottom over which the tailings must travel to the cylinder, and an alarm connected with said bars and so arranged relative 45 thereto as that said alarm will be sounded when a metallic body engages two or more of said bars.

4. In a threshing-machine, a shoe through which the tailings pass from the machine to the cylinder, a series of metallic bars arranged transversely of the shoe parallel with and in juxtaposition to each other and forming a bottom over which the tailings must pass to the cylinder, an electric alarm-circuit, connections between one line of said circuit and alternate individuals of the series of bars, and connections between the remaining line of the alarm-circuit and the remainder of the series of bars.

ELISIA H. OSBORN.
